APPARATUS FOR DETECTING INTERNAL
DAMAGE IN WOOD

Paul C. Trussell and Thomas Anthony Lambe, Vancouver, British Columbia, Canada, and John Vitins, Baden, Switzerland, assignors to British Columbia Research Council of the University of British Columbia, Vancouver, British Columbia, Canada

Filed July 3, 1961, Ser. No. 121,597

12 Claims. (Cl. 73—67.5)

This invention relates to a method and apparatus for detecting internal damage in wood and particularly damage caused by wood borers of the teredine type.

The teredine borer begins life as a small, free-swimming microscopic mollusc which impinges itself on submerged wood surfaces and burrows in the wood by means of the movements of its shells. The hole formed at the surface of the wood is at first not visible to the naked eye, and seldom exceeds one-eighth of an inch in diameter during the life of the borer. On the other hand, the borer continues to increase the diameter of its burrow as it drills inward until it becomes $\frac{1}{4}$ $\frac{1}{2}$ and sometimes $\frac{3}{4}$ of an inch. When many borers attack a wood surface, as is customarily the case, the surface reveals little damage aside from minuscule perforations, whereas the internal parts of the wood become excavated by the formation of a multiplicity of channels densely interlaced. What appears externally to be sound wooden member is internally a perforated mass.

When the borers are alive, their presence in the wood can be noticed by the projection of pairs of fine tubes extending outward from each fine pore at the surface of the wood. However, borers live only a maximum of two to three years in wood and in most cases much less because they exhaust the wood supply within their reach. This is particularly true when many borers are present in the wood. Accordingly, in most wooden structures which are not frequently inspected live borers are rarely found. More commonly the borers have lived their full life span and have died, leaving no superficial evidence of their damage except for tiny surface openings to their burrows. These openings commonly become covered by marine growth on the wood surface, and the external evidence of the attack is thus further concealed.

Making periodic inspection of wooden structures of marine-borer damage is important both for the safety of the equipment and personnel. For example, wharfs supported by wooden creosoted piling will eventually be weakened to a point of danger unless remedial measures are taken. Accurate inspection of piling will reveal when and what remedies are needed.

Heretofore the usual method for checking submerged wood for teredine borer attack has been to scrape or brush the surface of the wood gently (so that the creosoted coating is not damaged or perforated) and to look for the presence of the fine, surface holes. This procedure is time-consuming and inefficient. Often marine growth or particles of silt mask the borer openings. Weak sections in the wooden structures are frequently missed. An alternate method commonly used heretofore is to drill holes in the wood in search of damaged areas. Each drill hole is then tightly sealed by inserting a creosoted wooden plug therein. This method is extremely laborious and hazardous.

The present invention is concerned with a method and apparatus for detecting internal damage in wood which overcomes the drawbacks in the systems employed heretofore.

2

fore. Ideally what is desired is a non-destructive method by which the interior of the wood can be examined for borer damage. The method should be both quick and accurate and should be equally applicable to both untreated and chemically-impregnated wood. Further, the degree of damage should be measured mechanically and not subjectively by an operator. It is particularly important that the testing equipment be sufficiently sensitive to register that level of damage at which structural impairment commences. The equipment must be able to operate under water; rarely is it possible to remove the wooden structure from the water to make the examination for borer damage. Thus the equipment must be capable of revealing damage when the burrows of the borers are filled with water. It is also advantageous to have the testing equipment operable on wooden surfaces that do not require first cleaning of small marine growth, such as barnacles, tunicates, and fine plant growth.

Thus an object of the invention is to provide a method and apparatus which enables internal damage in submerged or water-soaked wood to be measured without causing further damage to the wood.

Another object of the present invention is to provide a method and apparatus which enables internal damage in submerged or water-soaked wood to be measured both accurately and expeditiously.

A further object of the invention is to provide a method and apparatus which enables internal damage in submerged or water-soaked wood to be measured without the necessity of any special preparation of the surface of the wood and in which there is no necessity to have access to the ends of the grain of the wood.

The present invention is based on the concept of detecting internal damage in submerged or water-soaked wood by means of sonic waves which are directed into and through the wood. The attenuation of the sound waves in their passage through the wood is then measured and from this an indication of the soundness of the wood is obtained.

In applying ultrasonic techniques to the detection of internal damage in submerged or water-soaked wood, many difficulties are encountered. These difficulties arise mainly because of the similarity of the acoustical properties of wood and water and also because of the high attenuation of sonic vibrations in wood. The situation is aggravated by the normal variation of these properties in sound wood.

Detection by echoes or by standing waves is not possible because of the absence of large flat surfaces of pronounced discontinuity at the damage. High attenuation also prevents the use of echoes with very short wave lengths. Pulse velocity methods are not sensitive to damage across the grain because of the similar velocities in water and wood in this direction and in the direction along the grain because the waves delayed by damage are obscured by faster waves transmitted along any outer layers of sound wood paralleling the damage.

A study was made of the usefulness of following the attenuation of sonic signals passing in directions across and substantially parallel to the grain of wood. Tests made in air using undamaged specimens and specimens which had been drilled with holes to simulate teredine burrows, gave essentially no distinction between the two specimens. Further, when water was used to improve the contact between the transmitting transducer and the wood and the receiving transducer and the wood, damage still could not be detected in wood intersected by air passages.

After exhaustive tests made on wood specimens in

water it was determined that in contrast to the results obtained where sound was directed along and across the grain of wood in air, there is a difference in the attenuation of sound waves directed substantially along the grain in the undamaged and borer-damaged specimens tested under water enabling varying degrees of damage to be revealed and to some extent the amount of damage to be measured. In particular it was found that there was a definite attenuation of the high velocity components of the waves in the damaged specimens. It was further determined that these wave components could be generated and detected after passage along through the grain of the specimen by transducers positioned adjacent a side surface of the specimen rather than at the ends of the specimen. This arrangement makes it possible to search for internal damage along the complete length of a specimen such as a piling, without requiring access to the ends of the piling.

It was thus discovered that sonic waves and specifically the high velocity components thereof travel with less loss of strength along the grain of sound wood than they do along the grain of wood which contains channels of water or live teredine specimens. It was found that a pulse of sonic waves applied to the surface of the wood generates a component which travels substantially in the direction of the grain in sound wood at essentially the velocity of a compressional wave in that direction and that the presence of internal damage in the submerged or water-soaked wood attenuates the before-mentioned component of the wave to an extent that increases with the amount of damage. The fact that the high-velocity component moves along the wood as a compressional wave and not as a surface wave makes it possible to determine internal damage in wood having a sound outer layer such, for example, as in creosote-impregnated piles. There is essentially no difference between water and teredine specimens in the wood insofar as sound transmission is concerned; this is to be expected since the borers are mainly water in composition. It was also discovered that the before-mentioned component of the sonic waves has the highest velocity and hence shortest time delay of any component of the wave action with the result that changes in attenuation can be determined before other components obscure the reception. The results also showed that the sonic waves and specifically the high-velocity components thereof travel much faster in sound wood than sonic waves travel in the surrounding water.

The present method of determining internal damage in wood comprises the steps of directing sound waves into and substantially along the grain of said wood and measuring the attenuation of the sound waves occurring in said wood, the degree of attenuation of said sound waves providing an indication of the soundness of the wood.

Apparatus for carrying out the method of this invention comprises means for generating a pulse of sonic waves, means for directing said waves into and substantially along the grain of the wood, means spaced from said generating means longitudinally in the direction of the wood grain for receiving the sound waves transmitted through the wood and means for measuring the attenuation of the sound waves transmitted through the wood thereby to provide an indication of the soundness of the wood.

Other features which may be included in accordance with the invention will be described hereinafter and referred to in the appended claims.

The invention will now be more particularly described in connection with the accompanying drawings which show by way of example one embodiment of the invention, and in which:

FIGURE 1 is a view in side elevation of one form of apparatus according to the invention shown attached to a section of wood piling,

FIGURE 2 is a sectional view on the line 2-2 of FIGURE 1, and

FIGURE 3 is a schematic diagram showing the layout of the apparatus and associated circuitry.

Referring to FIGURES 1 and 2 of the drawings, the apparatus comprises a shaft 10 provided adjacent each end with channel-shaped brackets 12 and 14. The shaft 10 is provided with a covering 16 of a suitable sound insulating material, such as rubber. The brackets 12 and 14 form mounts for clamping assemblies generally indicated at 18 and 20 which enable the apparatus to be clamped in position around a specimen such as a section of wood piling 22 which is to be tested. These clamping assemblies 18 and 20 are identical and it will thus be necessary to describe only one assembly 18 in detail. Clamping assembly 18 includes a pair of channel-shaped arm members 24 and 26, each pivotally connected at one end adjacent opposite ends of bracket 12. A spring 27 connected at opposite ends to arms 24 and 26 respectively, is effective to bias the arms about their pivots towards each other. Links 28 and 30 pivotally attached at one end to arms 24 and 26 respectively are pivotally interconnected at their other ends by a pin 32 which is slidably engaged in a slot 34 formed in an extension 36 of bracket 12. The links 28 and 30 are effective to guide the movement of arms 24 and 26 and the pin 32 and slot 34 coupling serves to limit the movement of these arms relative to each other. Angle members 38 and 40 are secured to and project normally from the free ends of arms 24 and 26 and are provided with U-shaped brackets 42 and 44 respectively. Rollers 46 and 48 are rotatably mounted on axles 50 and 52 journaled in brackets 42 and 44 respectively. Further rollers 54 and 56 rotatably mounted on axles 58 and 60 are journaled in U-shaped brackets 62 and 64 secured to shaft 10 intermediate the clamping assemblies 18 and 20. The clamping assemblies 18 and 20 are adapted to fit around the piling 22 with the rollers 46 and 48 engaging the periphery thereof and urging the piling against the backing rollers 54 and 56 under the action of the springs 27.

A pair of brackets 66 and 68 are slidably mounted on shaft 10 for movement therealong between the rollers 54 and 56. Bolts 70 and 72 enable the brackets 66 and 68 respectively to be locked in selected positions along the shaft 10.

A sound transmitter 74 having an acoustical reflector 75 is pivotally mounted on bracket 66 and a sound receiver 76 having an acoustical reflector 77 is pivotally mounted on bracket 68. The use of horn reflectors secures maximum transfer of sonic energy of the waves from the transmitter into and along the wood and from the wood to the receiver. The transmitter 74 comprises a pulse generator adapted to produce short electrical pulses which are applied to a transducer 78 causing the latter to resonate at its natural frequency of oscillation. The transmitting transducer 78 is effective to convert the energy of the electrical pulses developed by said pulse generator into short bursts of oscillation as sonic waves. Preferably, the transmitting transducer is of the magnetostrictive type producing waves at a frequency of 30 kilocycles per second. Other types of sound transducers such as piezo-electric or electromagnetic may however be used if desired. It is to be noted, however, that although it is preferred to use sonic waves with a frequency of 30 kilocycles per second, sonic waves with other frequencies may be used. It has been found that the upper limit of the frequency of the sound waves useful for determining damage in wood is 100 kilocycles per second. Waves of high frequency attenuate rapidly even in sound wood. Waves with a frequency of less than 1 kilocycle per second do not transmit well from the transmitter to the wood or from the wood to the receiver. The practical range of wave lengths has been found to lie between 10 and 80 kilocycles per second.

The transmitting transducer is energized from a suit-

able pulse generating circuit. As shown in FIGURE 3, the pulse generator may comprise a condenser C1 which is charged from a suitable power supply B through a resistance R. The condenser C1 is connected across the terminals of the transmitting transducer through contacts 90. The contacts 90 are periodically closed through a cam 92 mounted on a shaft 93 driven by a suitable motor 94 adapted to close the contacts 90 approximately 5 times per second. With the contacts closed, the condenser C1 is discharged across the transmitting transducer and in this manner pulses of electrical energy are supplied to the transmitting transducer at the rate of approximately 5 pulses per second.

The receiver includes a transducer 79, which may be of the magneto-strictive, piezo-electric or electromagnetic type, provided with a reflector 77 and adapted to convert sonic waves impinging thereon into electrical waves. The electrical waves from the receiver are applied through a step-up transformer 98 to a cathode ray oscilloscope 100 from which the attenuation of the signal transmitted through the piling can be measured. The sweep circuit connected to the horizontal deflector terminals of the oscilloscope is connected through a capacitor C2 to the pulse generator and its operation is initiated by and synchronized with the electrical pulses generated by the pulse generator. The synchronized horizontal time base is required for identifying the high velocity wave component for attenuation measurement.

For best sensitivity, the transmitter and receiver are directed towards each other preferably at an angle of 20 plus or minus 5 degrees to the perpendicular of the surface of the piling, although detection of damage can be obtained over the approximate range from 0 to 40 degrees to the perpendicular. The transmitter and receiver are maintained a constant distance from the surface of the piling by means of the backing rollers 54 and 56. Preferably, the transmitter reflector 75 and the receiver reflector 77 are positioned at a distance of up to approximately 15 centimeters from the surface of the piling, although greater distances could be used. It has been found that with the transmitter and receiver arranged in this manner, the sound waves are transmitted substantially along the grain of the wood under water with essentially no difference in the rate or strength of travel. This eliminates the variations in sound transmission associated with making transmitter-to-wood and wood-to-receiver contacts and enables more standardized testing conditions to be achieved. Furthermore, it avoids the complications which arise when barnacles, tunicates and other small marine growth are on the surface of the wood being tested. With the use of transmitter and receiver reflectors spaced a short distance from the wood surface, the small forms of marine growth have little effect and do not need to be removed to obtain reliable results on the internal condition of the wood.

In the operation of the device, the transmitter and receiver are secured in position on shaft 10 at a desired special separation of, for example, 1 meter. The distance separating the transmitter and receiver is of some importance and where the transmitting frequency is 30 kilocycles, the minimum distance for detecting damage under practical conditions has been about 80 centimeters. A longer distance is preferable because it gives a greater difference in the strength of the signal between damaged and undamaged wood. The extent to which the transmitter and the receiver can be moved apart, depends upon the attenuation of the sound by the wood. With 30 kilocycle equipment distances over 140 centimeters require too high an amplification at the receiver which is not desirable when working under field conditions. Lower frequency transducers, for example, 20 kilocycle may be slightly more favorable permitting a larger distance between the transmitter and the receiver and consequently may be more sensitive to damage closer to the centre and to the opposite side of the pile.

With the transmitter and receiver set up in this manner, pulsed sonic waves are directed from the transmitter into and along the grain of the piling. After passing in and down the piling for a distance of 1 meter, the signal is picked up by the receiver which, in turn, passes it along to the vertical amplifier input terminals of the cathode ray oscilloscope on which the strength of the signal and its time of passage for the fixed distance in the wood are measured. The sensitivity of the vertical amplifier of the oscilloscope 100 is adjusted for 20 milli-volts per centimeter. The sound wood permits the reception of sonic signals having an amplitude of 30 to 60 millimeters for the initial 200 microseconds of the received compressional wave, having a velocity of approximately 5000 meters per second, whereas seriously damaged wood gives signals with amplitudes of only 0-5 millimeters.

Greater sensitivity to borderline damage can be obtained by calibrating the apparatus prior to testing a specimen. The calibration is effected with a sample of sound wood of the same species and general shape as the specimen to be inspected such, for example, as a region of the specimen that is known to be sound for other reasons. The calibration is effected under the same conditions as those to be encountered in the tests on the specimen to be examined. With the apparatus mounted on the sample, the attenuation of signals transmitted through the sample with the specific time delay are then measured. Thereafter, when the apparatus is connected to the specimen under test and variations in attenuation of the transmitted signal from the figures obtained with the sample are noted, a more accurate indication of the internal damage in the specimen can be obtained.

In testing piling, the apparatus may be raised and lowered on the piling by means of a cable connected at one end to shaft 10 and connected at its other end to a suitable hoist mechanism, although preferably a diver is employed to move the apparatus. In the latter case, the diver can raise, lower and rotate the unit in a horizontal direction around the piling. The diver also facilitates the manipulation of the unit around obstructions, such as brace piling.

As shown, the transmitter and receiver are located on the same surface of the specimen being tested. This arrangement is the most convenient one and provides greater sensitivity to localized damage. However, it has been found that detection is possible with the transmitter and receiver angularly displaced up to 180 degrees from one another.

What we claim as our invention is:

1. Apparatus for detecting internal damage in a wood specimen submerged in water and caused by the action of wood borers and resulting in the creation of moisture-laden pockets within the wood comprising an elongated support member adapted to be positioned adjacent to and spaced from a surface of the specimen and positioned parallel to the grain of said specimen, a sound transmitter mounted on said support member and positioned to direct pulses of sound wave oscillations into the adjacent surface of the wood so as to form a series of compressional waves whose front travels parallel to the grain of the specimen, a sound receiver mounted on said support member and spaced from said transmitter longitudinally of said support member, said receiver adapted to detect the sound waves radiating from the surface of the wood after travelling along the grain of the specimen, the degree of attenuation of said sound waves providing an indication of the soundness of said specimen.

2. Apparatus for detecting internal damage in a wood specimen submerged in water and caused by the action of wood borers and resulting in the creation of moisture-laden pockets within the wood comprising an elongated support member, clamping means mounted on said support member adjacent each end thereof, said clamping means adapted for releasable engagement with the specimen to secure said support member to said specimen in

spaced relationship and substantially parallel to the grain thereof, a sound transmitter mounted on said support member and positioned to direct pulses of sound wave oscillations into the adjacent surface of the wood so as to form a series of compressional waves whose front travels parallel to the grain of the specimen, a sound receiver mounted on said support member and spaced from said transmitter longitudinally of said support member, said receiver adapted to detect the sound waves radiating from the surface of the wood after travelling along the grain of the specimen, the degree of attenuation of said sound waves providing an indication of the soundness of said specimen.

3. Apparatus as claimed in claim 2 wherein each of said clamping means comprises a bracket secured to said support member adjacent an end thereof, a pair of arms pivotally connected to said bracket adjacent one of their ends and having rollers rotatably mounted adjacent their other ends, and means normally urging said arms towards each other and operable to urge said rollers into engagement with the surface of said specimen.

4. Apparatus for detecting internal damage in a wood specimen submerged in water and caused by the action of wood borers and resulting in the creation of moisture-laden pockets within the wood comprising a support member adapted to be positioned adjacent to and spaced from said specimen parallel to the grain thereof, means for generating pulses of sound wave oscillations, said generating means mounted on said support member, means coupled to said generating means for directing said sound waves into the adjacent surface of the wood so as to form a series of compressional waves whose front travels parallel to the grain of the specimen, receiving means for detecting said sound waves after transmission thereof through the specimen, said receiving means mounted on said support member and spaced from said generating means, and means connected to said receiving means for indicating and measuring the attenuation of the sound waves radiating from the surface of the wood after travelling along the grain of the specimen, the degree of attenuation of said sound waves providing an indication of the soundness of the specimen.

5. Apparatus for detecting internal damage in a wood specimen submerged in water and caused by the action of wood borers and resulting in the creation of moisture-laden pockets within the wood comprising an elongated support member, means for releasably clamping said support member on to said specimen spaced therefrom and extending substantially parallel to the grain thereof, means for generating pulses of sound wave oscillations, said generating means mounted on said support member and spaced from a surface of said specimen, means coupled to said generating means for directing said sound waves into the adjacent surface of the wood so as to form a series of compressional waves whose front travels parallel to the grain of the specimen, receiving means for detecting said sound waves radiating from the surface of the wood after travelling along the grain of the specimen, said receiving means spaced from said surface and spaced from said generating means in a direction longitudinally of said support member, and means connected to said receiving means for indicating and measuring the attenuation of the sound waves transmitted through the specimen, the degree of attenuation of said sound waves providing an indication of the soundness of the specimen.

6. Apparatus for detecting internal damage in wood submerged in water comprising means generating pulses of sound waves, means directing said sound waves into the wood through a surface thereof that parallels the grain of said wood and so as to form a series of compressional waves whose front travels parallel to the grain of said wood, means spaced from said generating means in a direction lengthwise of the grain of the wood for detecting the sound waves radiating from the surface of the wood after travelling along the grain of said wood,

and means connected to said detecting means for indicating and measuring the attenuation of said sound waves transmitted through the wood, the degree of attenuation of said sound waves providing an indication of the soundness of said wood.

5 7. Apparatus for detecting internal damage in a wood specimen submerged in water and caused by the action of wood borers and resulting in the creation of moisture-laden pockets within the wood comprising a sound transmitter, a sound receiver, means retaining the transmitter and the receiver spaced from each other and spaced from a surface of the specimen that parallels the grain of said specimen, said sound transmitter being positioned to direct sound waves into said surface of the wood so as to form compressional waves whose front travels parallel to the grain of the specimen, and said sound receiver being positioned to detect the sound waves radiating from the surface of the wood after travelling along the grain of the specimen, the degree of attenuation of said sound waves providing an indication of the soundness of said specimen.

10 8. Apparatus as claimed in claim 7 in which the said sound waves have a frequency in the range 1 to 100 kilocycles per second.

15 9. Apparatus as claimed in claim 7 in which the transmitter and the receiver are directed substantially towards each other and inclined at an angle in the range 0 to 35 degrees to the normal of said surface of the wood.

20 10. Apparatus for detecting internal damage in a wood specimen submerged in water and caused by the action of wood borers and resulting in the creation of moisture-laden pockets within the wood comprising a sound transmitter, a sound receiver, means retaining the transmitter and the receiver spaced from each other and spaced from a surface of the specimen that parallels the grain of said specimen, said sound transmitter being positioned to direct pulses of sound waves into said surface of the wood so as to form a series of compressional waves whose front travels parallel to the grain of the specimen, said sound waves having a frequency in the range of 1 to 100 kilocycles per second with a pulse repetition rate of from 2 to 20 per second, and said sound receiver being positioned to detect the sound waves radiating from the surface of the wood after travelling along the grain of the specimen, the degree of attenuation of said sound waves providing an indication of the soundness of said specimen.

25 11. Apparatus for detecting internal damage in a wood specimen submerged in water and caused by the action of wood borers and resulting in the creation of moisture-laden pockets within the wood comprising a sound transmitter, a sound receiver, means retaining the transmitter and the receiver spaced approximately one meter from each other in a direction lengthwise of the grain of the wood and each spaced a distance up to approximately 15 centimeters from a surface of the wood that parallels said grain, said sound transmitter being positioned to direct sound waves into said surface of the wood so as to form compressional waves whose front travels parallel to the grain of the specimen, and said sound receiver being positioned to detect the sound waves radiating from the surface of the wood after travelling along the grain of the specimen, the degree of attenuation of said sound waves providing an indication of the soundness of said specimen.

30 12. Apparatus for detecting internal damage in wood submerged in water, comprising means generating sound waves, means directing said sound waves into the wood through a surface thereof that parallels the grain of said wood and so as to form compressional waves whose front travels parallel to the grain of said wood, means spaced from said generating means in a direction lengthwise of the grain of the wood for detecting the sound waves radiating from the surface of the wood after travelling along the grain of said wood, and means connected to said detecting means for indicating and measuring the attenuation of said sound waves transmitted through the

wood, the degree of attenuation of said sound waves providing an indication of the soundness of said wood.
